UNITED STATES PATENT OFFICE.

CHARLES H. RUTH, OF BRAWLEY, CALIFORNIA.

EXCAVATING-MACHINE.

1,287,760.

Specification of Letters Patent. Patented Dec. 17, 1918.

Application filed July 28, 1913. Serial No. 781,616.

To all whom it may concern:

Be it known that I, CHARLES H. RUTH, a citizen of the United States, residing at Brawley, in the county of Imperial, State of California, have invented certain new and useful Improvements in Excavating-Machines; and I do hereby declare the following to be a full, clear, and exact description of the invention, such as will enable others skilled in the art to which it appertains to make and use the same.

This invention relates to that type of excavating machines described in U. S. Patent No. 910,864, issued to me on Jan. 26, 1909.

An object of the present invention is to improve the excavating conveyer by mounting the same for transverse sliding movement on the main frame and for adjustment vertically whereby the excavating conveyer may be manipulated to suit various conditions of service in dredging ditches and the like.

A further object is to generally improve and simplify the conveyer buckets by the provision of hinged doors which are automatically operated to dump the buckets when the latter are elevated to a point suitable for discharge.

With the above objects in view the invention consists of certain novel details of construction and combination of parts herein-after fully described and claimed, it being understood that various modifications may be made in the minor details of construction within the scope of the appended claims.

In the accompanying drawings illustrating this invention:—

Figure 1 is a plan view of the excavating machine.

Fig. 2 is a side elevation of the machine.

Fig. 3 is a rear elevation of the machine.

Fig. 4 is an enlarged longitudinal sectional view through the excavating conveyer taken on the line 4—4 Fig. 1.

Fig. 5 is an enlarged cross sectional view taken on the line 5—5 Fig. 1 showing the conveyer driving shaft and its mountings.

Fig. 6 is a rear elevation showing the conveyer moved outwardly from the position shown in Fig. 3.

Referring now to the drawings in which like characters of reference designate similar parts, 10 designates in general the frame of the machine, the same including longitudinal sills 11 connected at intervals by cross sills 12, the frame being supported at the rear

end by spaced ground wheels 13 and at the front end by a dirigible ground wheel 14. The two rearmost cross sills 15 form a track.

Mounted to slide across the machine on this track is a carriage comprising a pair of standards 16 which are connected respectively to angleiron bars 17 that extend along the track, there being rollers 18 and 19 carried by the standards and bars and riding upon the track, the bars being retained on the track by means of yokes 20 carried by the bars at intervals apart and embracing the inner sides of the cross sills 15 forming the track. The standards are braced by guy wires 21 extending diagonally between the standards, while the bars 17 are braced by diagonal braces 22, and both the standards and bars are mutually braced by inclined braces 23. The carriage thus constructed may be moved back and forth along the track as desired.

The excavating conveyer about to be described is suspended from a single sleeve bearing 24 which projects transversely through vertical slots 25 formed in the standards, there being guide boxes 26 disposed on the sleeve bearing and slidably fitting in said slots. A feed screw 27 is threaded in the top of one of the standards and is turnably secured to one of the boxes 26, the feed screw being equipped with a handle lever 28 which permits of the feed screw being rotated to raise or lower the sleeve bearing bodily in the standards and thus adjust the secured end of the excavating conveyer vertically as desired.

The excavating conveyer comprises a pair of parallel sills 29 which are provided upon adjacent ends with bearings 30 which loosely receive the projecting end of the sleeve bearing and pivotally attach the sills to the sleeve bearing. The free ends of the sills are connected by a hanger yoke 31 and are further connected by a bail 32 which is secured to the cable 33 of a swinging boom 34 carried by one of the cross sills 12 of the main frame, the cable being controlled by means of a windlass 35 carried by said cross sill at the foot of the boom. As will be understood, by actuating the windlass the free end of the excavating conveyer may be swung up or down as desired.

A pair of large flange wheels 36 are secured on a shaft 36' that is carried in adjustable bearings 36" and a similar pair of large flange wheels 37 are secured to a shaft 38.

which connects the free ends of the sills 29, there being a pair of wheels 39 secured to a shaft 40 carried by the yoke 31. A pair of endless sprocket chains 41 are trained over 5 the flange wheel sprockets 39 and a pair of driving sprockets 42 which are secured to stub shafts 43 carried by the sills 29. These driving sprockets are of relatively small diameter and engage the underneath sides of 10 the sprocket chains, such sprockets furthermore projecting up between the sills 29 so that the lower sides of the chains are carried abruptly upwardly between the sills when passing over these sprockets.

15 Secured at spaced intervals to and spanning the sprocket chains 41 are buckets 44 each being in the form of a scoop with ears 45 at the front upper corners through which and the sprocket chains pivot pins 46 are 20 passed, the rear end of each bucket being loosely hung from the sprocket chains through the instrumentality of links 47 which are pivotally attached to the rear edges of the bucket top and to the sprocket 25 chains. A door 48 is hinged at the front end to the ears 45 by means of pivot pins 49 and is normally swung up into the bucket against the top thereof by the entering mud when the bucket enters the earth. The door 30 is provided with substantially triangular ears 50 which extend up through the skeleton top 51 of the bucket. As the bucket passes up between the sprockets 42 and then turns down at this point for dumping the 35 earth upon the bank of the ditch being excavated, the ears 50 impinge against abutment plates 52, of triangular form and which are bolted to the sills 29 and extend therebelow, with a resultant rocking forwardly of the door during passage of the 40 bucket along and underneath these abutment plates with a resultant ejection of the earth from the bucket. The buckets are thus dumped in succession whereby the excavated earth is piled on the bank of the 45 ditch.

For actuating the sprocket chains 41 I provide an extensible shaft 53 which extends through the sleeve bearing 24 and is 50 driven by a gas engine 54 through the instrumentality of a connecting shaft 55 that is connected to the shaft 53 by a universal joint 56 and to a line shaft 57, driven by the engine, by a universal joint 58. This 55 construction permits of the continuous actuation of the shaft 53 regardless of the position of the carriage upon the track. The shaft 53 projects through the sleeve bearing and is there equipped with a gear 60 which meshes with a gear 61 on the ad-

jacent stub shaft 43. The sleeve bearing 24 is severed on the opposite side of the conveyer from the just mentioned stub shaft and the ends flanged as at 61, there being spacing bolts 62 and spacing tubes 63 65 coupling the flanged ends together. A gear 64 is fixed on the shaft 53 between the flanges 61 and meshes with a gear 65 on the adjacent stub shaft 43.

The machine above described may be advanced along the ditch by means of a cable 66 one end of which may be fixed to any stationary support and the opposite end secured to a windlass 67 driven by the gas engine 54 through a suitable power transmission mechanism 68, as described in my former patent, or the machine may be drawn along by a traction engine, as preferred.

From the above description it will be seen that by virtue of the sliding carriage, the excavating conveyer may be moved transversely across the rear end of the machine to operate in wide ditches, and to accommodate this function, the rear axle 69 is formed of a plurality of telescoping members so that it may be extended outwardly to space apart the rear ground wheels 13 of the machine and positively prevent tilting of the machine when the excavating conveyer is moved outwardly as shown in Fig. 6.

It will also be seen that by virtue of the feed screw, the secured end of the excavating conveyer may be raised or lowered as desired to suit various conditions of service.

What is claimed, is:

1. In a device of the character described, a frame, a carriage, adjustable transversely of said frame, a sleeve mounted for vertical movement in said carriage, an endless chain of excavating buckets mounted on said sleeve, and means projecting through said sleeve for driving said endless chain of buckets.

2. In a device of the character described, a frame, a track on said frame extending transversely across the rear end thereof, a carriage mounted to move longitudinally of said track, a sleeve having one end extending beyond the rear of the main frame, and adjustably supported in said carriage, an endless chain of buckets mounted on said sleeve, and means projecting through said sleeve for operating said endless chain of buckets.

In testimony whereof, I affix my signature, in the presence of two witnesses.

CHARLES H. RUTH.
